AURTHUR W. BROWNE, OF BROOKLYN, NEW YORK, ASSIGNOR TO CHARLES R. SQUIRE, OF NEW YORK CITY.

Letters Patent No. 82,285, dated September 22, 1868.

IMPROVEMENT IN ROTARY STEAM-ENGINES.

The Schedule referred to in these Letters Patent and making part of the same.

TO ALL WHOM IT MAY CONCERN:

Be it known that I, AURTHUR W. BROWNE, of Brooklyn, county of Kings, and State of New York, have invented certain new and useful Improvements in Rotary Engines; and I do hereby declare the following to be a full, clear, and exact description of the same, reference being had to the accompanying drawing, making a part of this specification, in which—

Figure 1 is a vertical transverse section.

Figure 2 is a side elevation of the shell or cylinder with the upper portion broken away, for the purpose of showing the form of the steam-chamber in section.

Figure 3 represents one of the piston-slides detached.

Similar letters of reference denote corresponding parts in all the figures.

My invention relates to that class of rotary engines which have a drum inside of and eccentric to the shell or cylinder, and which is driven or made to revolve by the pressure of the steam upon a piston or pistons, which slide or vibrate in slots through the drum, at right angles to its axis, thus conforming readily to the contour of the shell.

My improvement consists in the construction and arrangement of parts whereby friction, and consequent wear and leakage, are largely prevented, and also whereby, on account of the engine being made more effectually self-packing, the waste of power from unavoidable wear is greatly reduced.

In order that others skilled in the manufacture of engines may be enabled to make and use my invention, I will proceed to describe it, with reference to the drawings.

A is the shell or outer cylinder, which may be made in one piece or in segments. For the sake of convenience, I shall speak of it as being in segments. It is composed of the abutment E E', provided with the pressure-chamber C, and the two cocks D D', the segment H H', and the two segments E H and E' H'. The segment H H' I find is best made an exact arc of ninety degrees, having a radius equal to the line H I. The segments E H and E' H' should be constructed so as to conduct the pistons G to and from the points E E' H H', with as little friction and jar as possible, but beyond that their exact shape is immaterial. They have each a port, F F', for the passage of steam, communicating with the pipes K K', which pipes are used alternately, for the purpose of induction or eduction, as the engine is run either forward or backward.

The steam-chamber of the cylinder, that is, the eccentric space extending around the drum B, from E to H, to H', to E', and transversed by the piston G, is made slightly flaring from its outer circumference toward its centre, so as to fit closely the piston, which is made a little wedging, as shown at G, fig. 2.

The abutment E E' is located on the side of the shell opposite to the arc H H', and must be long enough to bring the points E E' diametrically opposite to these points H H'. Each end of the abutment must fit accurately the drum B.

C is the pressure-chamber, provided with two cocks, D and D'

B is the drum, having slots or ways extending through from side to side, intersecting its axis, and at right angles with the same, through which the pistons G vibrate.

G G are the pistons, made in the usual form, except that at each end they are made in the form of a wedge, as shown in fig. 3.

Having described the construction of my engine, I will now proceed to explain its operation. Supposing that I wish it to run in the direction indicated by the arrows at H, fig. 1, I open the cock D, close cock D', and admit the steam by the pipe K; pressure is instantly applied to one of the pistons G, which is traversing the arc H H', and which is held closely in contact with the surface of the cylinder by the force of the steam acting upon the other end of the same piston in the pressure-chamber C. In case it is desired to run the engine in an opposite direction, I close the cock D, open D', and admit steam from the pipe K'.

It will be seen that this construction does away with nearly all the wear and consequent leakage of steam

past the piston, common to this class of engines, from the fact that while the piston is passing from H' to E', and is being pushed into the drum, as shown at E', it is not subjected to the pressure of the steam upon either end; consequently it moves easily and with but little wear. This results from the extension of the ports F and F', from the pipes K and K', up to the points H and H', as seen in fig. 1. Then, again, the unavoidable wear upon both the ends and the edges of the pistons is provided for by constructing them and the cylinder of the form described, and then, while the piston is traversing that portion of the cylinder between H and H' where steam is applied to it, and the leakage would occur, it (the piston) is made to adjust itself by means of the pressure of the steam in the chamber C acting upon the opposite end of each piston during the time occupied in passing between these points, thus making the engine self-packing.

Having thus described the construction and operation of my invention, what I claim, and wish to secure by Letters Patent, is—

1. The arrangement of the abutment E E', pressure-chamber C, and the cocks D and D'.
2. The pistons G, when constructed as set forth.
3. The construction of the segment H H', forming the chamber through which the piston passes while being acted upon by the steam, as herein set forth.
4. The arrangement in the shell of the rotary engine of the abutments E E', pressure-chamber C, and segments H H', substantially as set forth.

A. W. BROWNE.
